ELECTRIC DISCHARGE DEVICE

Ted E. Foulke, Chagrin Falls, Ohio, assignor to General Electric Company, a corporation of New York

Application October 16, 1948, Serial No. 54,873

4 Claims. (Cl. 313—54)

My invention relates to electric discharge devices, and more particularly to glow discharge or cold cathode devices having precise and uniform time-breakdown characteristics upon the application of voltage across terminals thereof, even though the devices are enclosed in containers which are impervious to light and substantially all other radiation.

It has been appreciated heretofore that when an electric discharge device is employed as a circuit controlling element having a desired predetermined time-breakdown or time-ionization characteristic it is desirable, and in many instances necessary, to construct the device so that a discharge is established in an accurately determinable interval of time after the application of voltage across the terminals or across the electrodes of the device. Short-time response characteristics and uniformity of ionization time, even though light or other ambient radiation is not present or available, are necessary in many applications. One of such applications is that where the discharge devices are totally enclosed in containers which are impervious to light and other radiation. Conventional present-day glow devices are so slow in response when shielded that they cannot reliably be controlled in less than about 2 seconds.

Generally speaking, it may be said that the time-breakdown, or ionization characteristic, of glow discharge devices is a function of the number of electrons available to be acted upon by the voltage impressed between cooperating electrodes, and which upon acceleration by the resulting electric field obtain a sufficient velocity to ionize the medium, vapor or gas, through which the discharge is to pass. Of course, these electrons may be furnished by thermionic emission, but such thermionic electrodes are not always satisfactory for all applications, particularly when there are limitations as to auxiliary sources of power, or as to the desirability for long life and permanency. Alternatively, in order to assure a sufficient number of electrons for ionization purposes, it has been proposed heretofore to place means for this purpose within the enclosing envelope or bulb of the device, but such arrangements have been found unsatisfactory because of the contamination produced inside the envelope and because of variations in the electrical characteristics produced thereby.

It is an object of my invention to provide a new and improved electric discharge device.

It is another object of my invention to provide a new and improved glow discharge device which has an accurate predetermined maximum time-breakdown characteristic of the order of 10^{-3} to 10^{-6} that of the present commercial devices even when employed in the dark, or being totally enclosed and shielded from ambient radiation.

It is a further object of my invention to provide a new and improved electric discharge device which may be employed as a lightning arrester.

It is a still further object of my invention to provide a new and improved electric discharge device having a

maximum breakdown or ionization time of the order of one microsecond, even in the absence of light or other radiation.

Briefly stated, in accordance with the illustrated embodiment of my invention, I provide an electric discharge device, such as a glow discharge device of the cold cathode type, in which cooperating electrodes are placed within an enclosing envelope. At least one of such electrodes is coated with an activating composition or coating of oxides of the alkaline earth metals. Outside the enclosure defined by the envelope, I provide a material of many years duration for producing radiation which causes the photo-emission of electrons in sufficient numbers to assure a maximum time of ionization or breakdown of the discharge path upon application of voltage across the electrodes thereof. The envelope is pervious to such radiation, and is preferably transmissive of radiation within the ultraviolet region down to about 3200 to 3300 Angstrom Units. The spectra of such radiation is correlated to the electrode surface so that a substantial part of the energy thereof is of a wavelength less than the threshold wavelength of such electrode surface.

For a better understanding of my invention reference may be had to the following description taken in connection with the accompanying drawing and its scope will be pointed out in the appended claims. The single figure of the drawing illustrates an embodiment of my invention as applied to a glow discharge device which is totally enclosed in a container impervious to light and other radiation.

Prior to considering the embodiment of my invention shown in the single figure of the drawing it is believed desirable to consider generally the fundamental relationships which exist in producing photo-emission of electrons from a metallic surface, or a surface which is provided with an activating coating. Generally, it may be stated that where the frequency of the radiation is greater than that corresponding to the critical or threshold frequency established by the chemical and physical properties of the surface irradiated, electrons will be emitted photo-electrically, at a velocity which is determined by the quanta relationship:

$$V_0e = \frac{1}{2}mv^2 = h\nu \quad (1)$$

45 V_0 =equivalent imparted energy in volts.

e =charge of the electron.

m =mass of the electron.

v =velocity.

h =universal constant.

50 ν =frequency.

The relationship between the work function ϕ and the critical or threshold frequency ν_0 is established by:

$$Ve = V_0e - \phi \quad e \quad (2)$$

$$Ve = h\nu - h\nu_0 \quad (3)$$

V =emitted velocity in volts.

ϕ =work function of the surface involved (in volts)

ν_0 =frequency corresponding to the long wavelength limit,

60 that is, the threshold frequency

$h\nu_0$ =minimum energy lost by an electron escaping from the surface.

If the quantity expressed by Equation 2 above is negative, no electrons will be emitted, or escape from the surface. This condition is that which exists when the quanta of energy is not greater than the energy corresponding to the threshold frequency.

Referring now particularly to the single figure of the drawing, I have there illustrated my invention as applied to a glow electric discharge device 1 which is totally enclosed and shielded by a container 2 which is constructed of a suitable metal such as brass, and which is

impervious to light and other radiation. The glow discharge device comprises an enclosing envelope 3 constructed of glass or quartz which is pervious and transparent to radiation within the blue and violet-blue portion of the visible spectrum and is also permeable to radiation within the ultraviolet region of the spectra, particularly that lying above approximately 3200 Angstrom Units. The transmitting characteristics of the material employed as the envelope 3 will of course be determined by the radiation desired for exciting the electrode surfaces described hereinafter. I provide electrodes 4 and 5 which may be constructed of nickel and which are supported by sealing structures 6 and 7 comprising part of a press or header 8 and through which extend lead-in conductors 9 and 10 constituting externally accessible terminals. The electrodes 4 and 5 preferably are long nickel cylinders supported by lead-in conductors 9 and 10.

Either one or both of the electrodes 4 and 5 may be provided with an activating coating 11 which is preferably formed by the addition of oxides of the alkaline earth metals to the conductor material constituting the electrodes. Preferably, I may employ oxides of barium and strontium to obtain a work-function thereof less than 2 volts and preferably less than 1.5 volts.

Within the envelope 3 I employ a suitable ionizable medium, such as a rare gas from the group consisting of argon, neon, krypton and xenon and mixtures thereof, at a suitable pressure depending upon the characteristics of the discharge device desired. For example, I have found that a gaseous composition comprising neon with about 0.8 per cent argon at a pressure ranging from 50 to 60 mm. of mercury has operated very satisfactorily in a device required to operate at 85 volts D. C. To obtain devices operable at other voltages either pressure or gas composition may be altered over wide limits. As a means for irradiating the electrode surfaces of either, or both, electrodes 4 and 5 by radiation correlated in frequency (and wavelength) to the threshold frequency (and wavelength) of the electrode surfaces, I provide material 12 which is positioned outside the enclosure provided by the envelope 3, and which may preferably be placed upon the exterior surface of the envelope 3. In this manner no contaminating products are produced inside the envelope 3 and therefore the electrical and operating characteristics of the glow discharge device 1 are not modified or changed.

The frequency of the radiation produced by the material 12 is preferably sufficiently greater than the critical or threshold frequency of the electrode surface 11 so that electrons are photo-emitted at a sufficient velocity to be present in the ionizable medium at the time voltage is impressed across the electrodes 4 and 5. The quantity of radiation produced by the material 12, and accordingly the intensity of the radiation impinging upon the activating surface 11 of electrode 4, is sufficiently high so that there are enough electrons in the ionizable medium at the time the voltage is impressed across electrodes 4 and 5 so that the ionization time is not only uniform but very much smaller than that previously obtainable in discharge devices of this nature. Heretofore, the time-breakdown characteristic or the ionization time has been in the order of magnitude of seconds or a substantial fraction thereof when completely shielded, whereas in the presence of light it is of the order of a few micro-seconds, and these characteristics and ionization times have not been uniform in any one type of device or in any one device. By employing my invention, I have been able to obtain not only uniform time-breakdown characteristics and ionization times, but I have also been able to reduce the shielded ionization time from the order of a second or more, to 1000 to 1 micro-seconds, dependent only on quantity and quality of radiation.

A suitable means and material for use in supplying

the radiation for effecting photo-emission of electrons from surface 11 may be a radio-active phosphor paint applied to the outside surface of the envelope 3. Although not limited thereto, one such paint may comprise a phosphor or fluorescent material comprising zinc sulphide activated with silver and a radio-active material such as radium sulphate which excites the fluorescent material or phosphor which in turn produces the radiation which is transmitted through the envelope 3 and impinges upon the surface 11.

I have found in choosing a material for this purpose that materials emitting within the blue region are very effective. Using a phosphor with maximum emission between 3300-4300 Angstrom units reduces the response time by a factor of 10, over a similar device with phosphor having a peak output at 4500 Angstrom units. Furthermore, radiation within the blue-violet region of the visible spectrum has also been found effective in causing appreciable photo-emission of electrons for this purpose but are of substantially lower efficiency.

As a further improvement for very short ionizing times I provide caesium as an ingredient of the gaseous composition, and caesium may be added to the discharge in the form of caesium-dichromate which upon evaporation during processing of the device will of course settle in some measure upon the activating surface 11. I have found that where caesium is employed the maximum photo-electric current or the maximum photo-emission appears to occur at about 4300 Angstrom units, whereas where oxides of barium and strontium are employed as the activating surface 11 the maximum photo-emission appears to occur within the range from about 3200 to 4000 Angstrom units, and more particularly between 3300 and 3800 Angstrom units. In the latter instance, of course the ionizable medium is a rare gas or mixture of rare gases.

Inasmuch as uniform electrical characteristics of the discharge device 1 are highly important and vital, I have provided means for preventing electrical leakage between electrodes 4 and 5 and inleads 9-10, which in some instances may be occasioned by the use of caesium which settles on the stems and seal structures. This leakage prevention expedient comprises placing oxides of light metals, such as oxides of calcium and magnesium, on the supporting structures or seals 6 and 7 to repel and prevent deposition of caesium thereon. Light metal oxides may also perform a function in addition to the prevention of electrical leakage, and that is the emission of secondary high speed electrons from the electrode surfaces by radioactive bombardment by substances, such as thorium, which do not poison the gas, or ionizable medium, and which do not attack the electrode surfaces.

Where it is desirable to provide within the envelope 3 materials which cause secondary particle emission from material placed on the elements 6 and 7, I may employ the following composition on the supporting structures 6 and 7, which produce alpha, beta and gamma rays to assist in the ionization of the medium employed and hence to provide and have present a small but permanent and additive source of ionization:

100 grams of thorium oxide
10 grams of magnesium oxide
10 grams of calcium oxide
65 10 grams of beryllium oxide
10 grams of aluminum oxide

In this manner, the particles emitted by the thorium oxide produce secondary particle emission from the light metal oxides, which secondary emission produces ionization of the gas.

By employing the above-described features in the construction of glow discharge devices I have been able to reduce the shielded ionization time from seconds to several, such as 1 to 3, micro-seconds, and in some instances

to 0.1 micro-second. Discharge devices constructed in accordance with the teachings of my invention not only have afforded reduction in the ionization and response times but have also afforded uniformity of response characteristics without deterioration of other electrical properties.

Electric discharge devices constituting my invention may be employed for several purposes such as in lightning arresting devices, and particularly in any electrical circuit requiring reliable response within a predetermined maximum interval of time ranging to values as small as one micro-second and less. These time-response characteristics are obtained without sacrificing the electrical characteristics, such as the breakdown voltage and the discharge sustaining voltage which of course, vary depending upon the design of each device incorporating my invention.

What I claim as new and desire to secure by Letters Patent of the United States is:

1. A glow discharge device having a precise time-breakdown characteristic upon application of voltage thereto, comprising an enclosing envelope permeable to radiation having a wavelength between about 3200 and 4900 Angstrom units, a pair of cooperating electrodes in said envelope at least one of said electrodes being a cold cathode having an activating coating of oxides of the alkaline earth metals, sealing and supporting structure for said electrodes, an ionizable medium within the envelope comprising a gas from the group consisting of the rare gases and caesium, material positioned externally of and contiguous said envelope and producing radiation having wavelength between about 3200 and 4900 Angstrom units for effecting photo-emission of electrons from said one electrode, and oxide coating on said structure of light metal which repels cesium for preventing leakage between said electrodes.

2. An electric discharge device comprising an enclosing envelope, a pair of cooperating electrodes in said envelope at least one of said electrodes being a cold cathode having an activating composition thereon comprising an oxide of the alkaline earth metals, an ionizable medium within said envelope comprising a rare gas and caesium, radio-active fluorescent material positioned externally of and contiguous said envelope and producing radiation which effects the photo-emission of electrons from said one electrode in order to ionize said medium, and an oxide of the group of metals consisting of magnesium, calcium and mixtures thereof upon the sealing

and supporting structure for said electrodes to prevent the deposition of caesium thereon.

3. An electric discharge device comprising an enclosing envelope, a pair of co-operating electrodes in said envelope at least one of said electrodes being a cold cathode having an activating composition thereon comprising an oxide of the alkaline earth metals, an ionizable medium within said envelope comprising a rare gas, material positioned externally of and contiguous said envelope and producing radiation which effects the photo-emission of electrons from said one electrode in order to ionize said medium, upon application of voltage, and a composition positioned on the sealing and supporting structure for said electrodes comprising an oxide of the group of metals consisting of thorium, magnesium, beryllium, aluminum and mixtures thereof for producing rays to assist in the ionization of said medium by bombarding said medium to thereby cause additional ionization.
4. A glow discharge device having a precise time-breakdown characteristic upon application of voltage thereto comprising in combination an enclosing envelope pervious to blue and ultraviolet radiation, a pair of cooperating electrodes in said envelope at least one of which is a cold cathode and has thereon an activating composition having a work function less than two volts, a rare gas in said envelope, and phosphor of radioactive silver-activated zinc sulphide positioned externally of and contiguous said envelope and emitting radiation which effects photo-emission of electrons from said one electrode, the combination imparting to the device a maximum time-breakdown characteristic of the order of a few microseconds even when shielded from the light.
